UNITED STATES PATENT OFFICE.

CLARENCE HOWLETT, OF LA PORTE, INDIANA.

CLOTHES WRINGER.

Application filed November 21, 1924. Serial No. 751,229.

The invention relates to feeding attachments for clothes wringers, and has for its object to provide a device of this character on which articles of clothing to be wrung may be hung and fed between the rollers by the rotation of the device, incident to the gripping thereof by the adjacent surfaces of the rolls.

A further object is to provide a clothes wringer attachment comprising a rotatable member adjacent one side of the rolls, and in the plane of the engaging surfaces of the rolls, and on opposite arms of which members articles of clothing may be hung and carried between the rolls for wringing operation by the gripping of the rotatable member by the rollers upon an initial manual movement of the rotatable member. Also to provide means whereby the rotatable member will be rotated by the rolls substantially 180 degrees, thereby placing the oppositely disposed arms thereof alternately in position at one side of the wringer for the reception of articles of clothing to be passed between the rolls. The device is primarily designed to obviate the mashing of fingers of wringer operators, which is a common difficulty experienced with wringers as at present constructed and especially power driven ones.

A further object is to provide one side of the wringer frame with a horizontally disposed bearing ring on which is rotatably mounted the feeding member, and to provide the rotatable feeding member with oppositely disposed recesses preferably at 90 degrees to the arms thereof, and which recesses, when the arms are at a right angle to the rolls, receive the ends of the rollers therein and stop the rotation of the rotatable member, until an initial manual movement is imparted to the rotatable member for moving the same to a position where it will be gripped by said ends of the rolls.

A further object is to provide friction means cooperating with the rotatable member for preventing too easy rotation thereof, for instance when hanging articles on the arms thereof.

With the above and other objects in view the invention resides in the combination and arrangement of parts as hereinafter set forth, shown in the drawing, described and claimed, it being understood that changes in the precise embodiment of the invention may be made within the scope of what is

claimed without departing from the spirit of the invention.

In the drawing:

Figure 1 is a front elevation of a conventional form of wringer showing the feeding device applied thereto.

Figure 2 is a vertical transverse sectional view taken on line 2—2 of Figure 1.

Figure 3 is a horizontal sectional view 65 through one side of the wringer taken on line 3—3 of Figure 1.

Figure 4 is a detail sectional view through one side of the feeding device taken on line 4—4 of Figure 3.

Referring to the drawing, the numeral 1 designates the frame of a conventional form of wringer, which frame is provided with the usual vertical side bars 2. Rotatably mounted within the frame 1 are horizontally disposed rolls 3, preferably formed from yieldable material. Rolls 3 are rotated in the direction of the arrows *a* by means of a drive pulley 4 and gears 5 in the usual manner, and to which pulley 4 a belt may be attached from a motor or other source of power. The upper roll 3 are yieldably mounted in the usual manner, and it has been found in conventional forms of wringers, especially those that are power driven, the fingers of the operators are often mashed in feeding articles of clothing between the rolls. To obviate this difficulty one of the side bars 2 is provided with spaced castings 6, the space between which castings registers with and is in the same horizontal plane as the adjacent sides of the rolls 3. Castings 6 may be formed integral with the side member 2, and are provided with registering arcuately shaped members 7 in a horizontal plane, and the lower member 7 is provided with an annular groove 8, in which is rotatably mounted a feeding plate 9. Plate 9 is disposed in substantially the same plane as the engaging surfaces of the roll 3, and at opposite sides thereof is provided with arms 10, also in said plane.

In operation the operator hangs an article of clothing on one of the arms 10, partially rotates the plate 9 until the rolls 3 move out of the oppositely disposed recesses 11 in the plate 9, thereby gripping the plate during the rotation of the rolls in the direction of the arrows *a* and completing the movement of the plate and arm 10 on which an article has been hung between the roll, thereby wringing the article which is fed between

the rolls by the arms on which it has been hung. In the meantime the opposite arm 10 is moved to the front side of the wringer, ready to receive another article to be wrung. When the rolls, after the wringing operation, again have their ends disposed in the other recess 11, the member 9 will be stopped until an article is hung on the arm 10 which has been moved to position for use, 10 and the operation continues in the manner above set forth. It will be noted that the recesses 11 are opposite each other and substantially 90° from the arms 10, therefore the arms will always stop at a right angle 15 to the rolls, and the device will not be rotated by the rolls until a partial rotation is imparted thereto, manually, by the operator, therefore the danger of the device rotating unexpectedly or at equal intervals of time 20 is obviated. To prevent accidental movement of the device, a friction member 12, preferably of leather, is provided, which member engages the upper side of the plate 7, and is disposed in a recess 13 thereof, and 25 with which leather member 12 a set screw 14 cooperates, and by adjusting said set screw 14, the frictional holding of the plate 9 is varied as desired. Arcuately shaped members 7 are preferably rigidly secured together by means of screws 15, however it is understood other means may be used if desired. The plate 9 and its arms 10 are preferably formed from relatively thin metal, for instance sheet metal, and as the plate moves 30 between the rolls, it will be partially imbedded in the yieldable material from which the rolls 3 are formed, thereby avoiding the danger of the rolls being spread apart to an extent, which may in any way effect their 35 wringing operation.

From the above it will be seen that a clothes feeding device is provided for a clothes wringer, which is simple in construction, positive in its operation, and one 45 wherein the device is automatically rotated and carried between the rolls by the frictional engagement therewith and with an article thereon of the rolls. It will also be seen that the device is provided with means 50 whereby it will automatically stop after an article has been passed through the wringing machine and the starting of the device is accomplished by a partial rotating of the feeding device to a position where it will 55 be gripped by the rolls.

The invention having been set forth what is claimed as new and useful is:—

1. A feeding device for a wringer provided with wringer rolls and side rails, comprising a flat clothes receiving member, means for rotatably supporting the same and means for attaching the supporting means to one of the side rails of the wringer substantially with the receiving member in a plane passing through the line defining the bite of the rolls.

2. A feeding device for a wringer provided with wringer rolls and side rails, comprising a guide member carried by one of the rails, a flat clothes receiving member rotatably mounted on the guide member and having a recess in one side thereof for the reception of the ends of the rolls, said clothes receiving member being supported substantially in a plane passing through the line defining the bite of the rolls.

3. A feeding device for a wringer provided with wringer rolls and side rails, comprising a guide member carried by one of the rails, a flat member rotatably mounted on the guide member, flat oppositely extending arms carried by the flat member and adapted to receive articles of clothing, said flat member and flat arms being supported substantially in a plane passing through the line defining the bite of the rolls.

4. A feeding device for a wringer provided with wringer rolls and side rails, comprising a guide member carried by one of the rails, a flat member rotatably mounted on the guide member, flat clothes receiving arms carried by the flat member, friction means engaging the flat member and carried by the guide member, said flat member and flat arms being supported substantially in a plane passing through the line defining the bite of the rolls.

5. A feeding device for a wringer provided with wringer rolls and side rails, comprising a flat clothes receiving member having oppositely disposed recesses therein for the reception alternately of the adjacent ends of the rolls, and means for rotatably supporting the same on one of the side rails of the wringer substantially with the clothes receiving member in a plane passing through the line defining the bite of the rolls.

In testimony whereof I affix my signature.
CLARENCE HOWLETT.
